INVENTOR
BY *Victor J. Evans*
ATTORNEY

UNITED STATES PATENT OFFICE.

WALTER H. WOOD, OF FOREST, IDAHO.

SAW SET.

Application filed March 8, 1920. Serial No. 363,967.

To all whom it may concern:

Be it known that I, WALTER H. Wood, a citizen of the United States, residing at Forest, in the county of Lewis and State 5 of Idaho, have invented new and useful Improvements in Saw Sets, of which the following is a specification.

This invention relates to a saw set and the object of the present invention is to improve and simplify the construction of the device forming the subject matter of my Patent No. 1,190,972, dated July 11, 1916.

This invention also consists in certain other features of construction and in the 15 combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a front view of the device.

Figure 2 is a longitudinal sectional view.

Figure 3 is a detail view of the gauge plate.

Figure 4 is an edge view.

30 In these views 1 indicates the body of the device which is formed from one piece of material. This body is provided with the slot 2 which extends from the small end longitudinally on the body, to a point an appreciable distance from the large end. This slot is to receive the saw blade as will be understood. A triangular-shaped gauge plate 3 is placed in the inner end of this slot and this inner end is enlarged and pro-

40 vided with an inclined wall as at 4 to form a space for the saw teeth. The body is provided with a chamber 5 which slopes inwardly from one face of the body, the body being of less thickness at its large end. The

45 outer end of this chamber begins at the junction of the two parts. The slot divides the chamber in half and in one half of the chamber is arranged the anvil 6 which is carried by the thumb bolt 7, said bolt pass-

50 ing through the slot 8 formed in the side of the body and communicating with said chamber. The other half of the chamber receives the hammer 9 which is carried by the screw threaded stem 10, which passes

through the screw threaded boss 11 formed 55 on the body, said stem being provided with the hand engaging disc 12. The reduced end of the stem engages an under cut slot 13 in the hammer as described in the before mentioned patent. A clamping bolt 14 may 60 be provided for clamping the saw blade in the device as described in the said patent. A gauge 15 may be placed on the body to indicate the position of the anvil for different sizes of saws; then when the anvil 65 is moved longitudinally the numerals on the gauge plate 15 will register the size of the saw. The plate 3 is of wedge-shape so that it may be driven into place and held by friction. 70

The device operates as described in the patent, the hammer being forced inwardly to press the saw teeth against the anvil by turning the stem by the handle, said anvil being adjustable by moving the screw bolt 75 in the slot 8.

It is thought from the foregoing description that the advantages and novel features of my invention will be readily apparent.

I desire it to be understood that I may 80 make changes in the construction and in the combination and arrangement of the several parts, provided that such changes fall within the scope of the appended claim.

What I claim is:—

85 A saw set comprising a body formed from one piece of material and having a screw threaded boss thereon, having a saw receiving slot therein, a chamber divided by said slot into two halves, a thumb bolt passing 90 through a slot formed in the side of the body and communicating with said chamber, an anvil carried by said thumb bolt, a screw threaded stem passing through said screw threaded boss formed on the body and a 95 hand engaging disk provided thereon, a hammer carried by said screw threaded stem and located in one half of the chamber, a triangular shaped gauge plate placed in the inner end of the slot formed in said body 100 and said inner end being enlarged and provided with an inclined wall to form a space for the saw teeth, said screw threaded stem having a reduced end to engage an under cut slot formed in the hammer, and means 105 for clamping the saw blade in the device.

In testimony whereof I affix my signature.
WALTER H. WOOD.
